UNITED STATES PATENT OFFICE.

EDWARD A. LANGENBACH, OF CANTON, OHIO.

DESIGN FOR A METALLIC BORDER-PLATE.

SPECIFICATION forming part of Design No. 26,414, dated December 15, 1896.

Application filed November 9, 1896. Serial No. 611,573. Term of patent 7 years.

To all whom it may concern:

Be it known that I, EDWARD A. LANGENBACH, a citizen of the United States, and a resident of Canton, county of Stark, State of Ohio, have invented a new and original Design for Metallic Border-Plates, of which the following is a full, clear, and exact description, reference being had to the accompanying drawings, making part of this specification.

My invention relates to a new design for a sheet-metal border; and it consists of a border of the configuration and ornamentation shown in the accompanying drawings, in which—

Figure 1 is a view in elevation of my invention, and Fig. 2 is a sectional view of the same.

The leading feature of my design is a sheet of metal having the roll A and the curved panels B, ornamented as follows: The roll A is provided with a series of horizontal parallel straight lines crossed by a series of vertical parallel lines, between which are a series

of parallel curved lines. Above the roll are series of horizontal lines connected by a series of vertical lines, and above these lines are 25 circular and elongated beads.

The panels B below the roll are ornamented by fanciful figures C, as shown in Fig. 1. These figures are formed of a cluster of leaves, cones, circles, straight and curved 30 lines, scrolls, &c.

A border of the configuration and ornamentation shown in the accompanying drawings is pleasing to the eye and materially adds to the surroundings. 35

What I claim is—

The design for a sheet-metal border as herein shown and described.

In testimony whereof I have hereunto set my hand this 28th day of October, A. D. 1896. 40

EDWARD A. LANGENBACH.
